UNITED STATES PATENT OFFICE

2,476,959

PULSE SIGNALING SYSTEM

Prafulla Kumar Chatterjea and Charles Thomas Scully, London, England, assignors, by mesne assignments, to International Standard Electric Corporation, New York, N. Y., a corporation of Delaware

Application May 1, 1945, Serial No. 591,270
In Great Britain May 2, 1944

7 Claims. (Cl. 332—9)

1

The present invention relates to electrical pulse signalling systems and has for its object to provide arrangements for producing electrical pulses particularly time phase and duration modulated pulses whose unmodulated duration is very short, that is very short compared to the repetition period of the pulses, for example, of the order of 10%.

In accordance with the invention, an arrangement for producing modulated electrical pulses comprises a normally inoperative or quiescent oscillation generator, which is rendered operative or active by a repetitive wave of the desired pulse frequency once per period of the said repetitive wave, means for varying a factor of the arrangement which affects a characteristic of the generated oscillations by a modulation signal wave; for example, varying the frequency of the repetitive wave to produce time-phase modulated pulses; or the frequency of the generated oscillations to produce duration modulated pulses and means for eliminating the positive or negative half cycles of the generated oscillations.

In order to produce duration modulated pulses, the frequency of the generated oscillations is varied in accordance with the amplitude of a signal wave, for example, by varying the frequency-determining circuit of the oscillation generator. Thus the period of the half-cycle of the generated frequency varies in accordance with the amplitude of the modulating signal wave and the instant of generation of the half cycles is determined by the repetitive wave of the desired pulse frequency. The pulses in the output of the oscillation generator will be substantially half sine wave in form and may be transformed to rectangular or other shape in any known manner, as for example, by amplifying and amplitude limiting to produce pulses of rectangular form.

To produce time-phase modulated pulses, the source of pulse repetition frequency is frequency or phase modulated in accordance with the amplitude of a signal wave. The frequency of the oscillation generator is maintained constant but the oscillations are generated at intervals depending upon the frequency of the source. As in the case of duration modulation pulses, the pulses in the output of the oscillation generator may be shaped in any desired manner.

In an embodiment of the invention about to be described an electron discharge oscillation generator is designed to produce oscillations whose period is twice the desired mean duration of the pulses and to have the negative (or positive) half waves eliminated; is biased to be normally in-

2

operative and is rendered operative intermittently by a repetitive wave of the desired pulse repetition frequency and the pulses in the output of the generator are modulated by modulating one of the factors governing one of the characteristics of the pulses, for example the frequency of the repetitive wave which results in time-phase modulation of the generator output pulses, or the frequency of the generator which results in duration modulation of the pulses. In order to produce a single pulse during each repetitive wave period, the repetitive wave is applied to the oscillation generator so that it renders this latter operative for less than a period of the oscillation generated.

The accompanying drawings show by way of example, the circuit arrangements of two embodiments of the invention, in Figure 1 for producing duration modulated pulses and in Figure 2 for producing time-phase modulated pulses.

In Figure 1 the arrangement comprises an electron discharge device oscillation generator represented as a triode V1 with a frequency determining circuit comprising parallel connected inductance L1 and capacity C1 connected in the anode circuit and coupled for regenerative feedback to the grid by inductive coupling coil L2. In series in the grid-cathode circuit is the auxiliary driving source S of the desired pulse repetition frequency. This source may comprise a sinusoidal but preferably saw tooth or other peak form of repetition wave and the grid bias of the valve V1 is so adjusted that normally V1 is nonconductive but when the wave from auxiliary source S is applied, the valve becomes conductive and the oscillator becomes operative at some point in the cycle of the wave. The period of the oscillator is adjusted to be twice the desired duration of the required pulses and the amplitude of the wave from source S is adjusted to be such that the oscillator is operative for not more than a period of the generated frequency and for not less than half said period. A rectifier D is connected across the frequency determining circuit L1, C1 of valve V1 to absorb or eliminate alternate half cycles of the generated oscillation.

The bias on V1 is obtained by means of the resistance chain r2, r3 connected across the high tension supply and by varying the relative values of r2 and r3 as will be well understood. Resistance r1 is connected in the grid circuit, and the condenser C2 is connected across r2 as is usual and well known. The output pulses are taken from the anode terminal shown at O.

To produce duration modulated pulses, accord-

ing to this invention the frequency of the oscillations generated by V_1 is varied in accordance with the amplitude variations of the signal wave. This may be effected in any known manner by varying one of the components of the frequency determining circuit L_1, C_1 . As shown in the drawing use is made of the Miller effect to vary the capacity of the frequency determining circuit and to this end a pentode valve V_2 is connected across the valve oscillator circuit, that is, across the valve V_1 and circuit $L_1 C_1$ in series and the modulating signal wave which may, for example, be speech, is applied to the control grid G_1 of the pentode V_2 to provide the capacity variation as is well known. Thus the period of the oscillations generated in the oscillator varies with the signal wave amplitude and hence the pulses produced in the anode circuit, which consist of alternate half cycles of the oscillations are duration modulated in accordance with the amplitude variation of the signal modulating wave. The half-oscillation pulses may be shaped into rectangular form by any known means, such as already stated, in the well known manner of amplifying and amplitude limiting.

Whilst a particular oscillation generator has been given by way of example, it will be understood that any other type of oscillation generator may be utilised and any other means for varying the frequency under the control of the modulating signal wave may be employed.

In order to obtain time phased modulated pulses, the arrangement shown in Figure 2 may be used. In this figure, parts the same as those in Figure 1 are given like designations. The valve V_2 is omitted, and the frequency of the generated oscillations remains constant. However, any known means is provided for frequency or phase modulating the source S whose mean frequency is the desired pulse repetition frequency, by means of the modulating signal wave from source W . The source S takes the form of a variable frequency oscillation generator, the waves being applied to control the operation of the oscillator. In the arrangement shown in Figure 2 means may be provided to maintain the frequency constant so that the duration of the output pulses is maintained strictly constant.

As mentioned in relation to Figure 1, the pulses in the output of the arrangement shown in Figure 2 may be amplified and amplitude limited to produce pulses of rectangular wave form.

It will be easily seen by those versed in the art that to obtain amplitude modulated pulses from V_1 it is only necessary to maintain the frequency of source S constant and to modulate the amplitude of these oscillations by the modulating signal wave before application to vary the bias on V_1 or else to apply the modulating wave directly to the grid of V_1 to vary the gain thereof.

Referring again to Figure 1, it may be found that the reactance valve V_2 is required to present inductive or capacitive reactance in practice depending upon the type of oscillator circuit employed as well as the part of the circuit controlled by the reactance valve.

The optimum design of coils L_1, L_2 in the type of circuit shown in Figure 1 is the design which has the greatest coupling and a moderate "Q." The tuning of such a circuit would thus avoid amplitude modification to any sensible extent.

In embodiments where the valve V_1 , shown in the example as a triode, is a multi-grid valve such as a pentode, the pulse repetition frequency from source S may be applied to other electrodes than

the control grid, for example to the suppressor grid and/or screen grid.

What is claimed is:

1. An arrangement for producing modulated electrical pulses comprising a normally inoperative oscillation generator, a source of repetitive waves, of the desired pulse frequency, means for applying waves from said source to said generator to render it operative once per period of the said repetitive wave, a source of signal waves, means for varying by modulating with the signal waves from said source a factor of the system which affects a characteristic of the generated oscillations, and means for eliminating half-cycles of the generated oscillations of a given polarity.
2. An arrangement for producing modulated electrical pulses comprising an oscillation generator whose period is twice the desired mean pulse duration, bias means for rendering said generator normally inoperative, an auxiliary generator of waves of pulse repetition frequency, means for applying the output of said auxiliary generator to render said oscillation generator operative once every repetition period, means for eliminating alternate half cycles of the generated oscillations from said oscillation generator and means for varying the frequency of one of said generators in accordance with the amplitude of a modulating signal.
3. An arrangement for producing duration modulated electrical pulses comprising an oscillation generator of higher frequency than the pulse repetition frequency, bias means for rendering said generator normally inoperative, an auxiliary source of waves of pulse repetition frequency, means for applying the output of said auxiliary source to render the said generator operative once every said repetition period, means for eliminating half cycles of the generated oscillations of given polarity and means for varying the frequency of the generated oscillations in accordance with the amplitude of a modulating signal wave.
4. An arrangement for producing time-phase modulated electrical pulses comprising an oscillation generator of higher frequency than the mean pulse repetition frequency, bias means for rendering said generator normally inoperative, an auxiliary source of waves of pulse repetition frequency, means for applying the output of said auxiliary source to render said generator operative once every said repetition period, means for eliminating half cycles of the generated oscillations of a given polarity and means modulating the angular velocity of the waves of said auxiliary source in accordance with the amplitude of a modulating signal.
5. An arrangement as claimed in preceding claim 2 wherein said oscillation generator comprises an electron discharge device whose grid is negatively biassed to render said generator normally inoperative, and means for applying the said repetitive wave form to said grid to overcome the negative bias and render said generator operative.
6. An arrangement as claimed in preceding claim 2 wherein the said oscillation generator generates one oscillation per period of said repetitive wave.
7. An arrangement as claimed in claim 3 wherein the means for varying the frequency of the generated oscillations comprises an electron discharge device connected across the frequency determining element of said generator and means for applying the modulating signal wave to said

discharge device to vary the impedance thereof according to the amplitude of said signal wave.
